UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

LINK-LAST.

No. 902,302.

Specification of Letters Patent.

Patented Oct. 27, 1908.

Application filed January 4, 1908. Serial No. 409,262.

To all whom it may concern:

Be it known that I, EDWIN O. KRENTLER, a citizen of the United States, residing at Detroit, Michigan, have invented an Improvement in Link-Lasts, of which the following description, in connection with the accompanying drawings, is a specification, like letters on the drawings representing like parts.

10 My invention is a hinged last having two objects in view, viz., inexpensive construction and ability to remain in shortened position when bottom up on the jack for receiving a shoe in the process of relasting.

15 Besides these objects my invention provides an exceedingly strong last, as scarcely any of the wood is cut out, a very simple last, as only one link hinge is used, and a very stable last, as the hinge is preferably horizontal and located about the middle of the last measuring from top to bottom.

In the drawings, in which I have shown my invention, Figure 1 is a view in side elevation, parts being broken away, showing 25 the last in its lengthened position, and Fig. 2 is a similar view showing the last in the position it assumes on a jack ready to receive a shoe.

In carrying out my invention I have preferred to give the last mainly a sliding movement as distinguished from a wholly swinging movement, and accordingly my invention resides in the particular lines of cut whereby the last has an exceedingly 35 stable position both when lengthened and when shortened, and the location and arrangement of the pivoted link hinge which co-operates with the end formation or line of cut to permit and require the precise 40 movement necessary in order to accomplish my object.

Beginning at a convenient point 1 in the shank of the last or in front of the heel-part, I sever the forepart 2 from the heel-part 3 by a short vertical cut 4 terminating at 5 and thence an oblique straight or plane secant line 6; which in the forepart is preferably deflected at 7 and thence continues to the crown of the instep at 8, the adjacent 50 portion of the heel-part being preferably cut off at 9 so as not to interfere with the lacing of the shoe. On pivots or transverse pins 10 and 11 is mounted to swing freely, a relatively short and preferably heavy 55 metal link or hinge 12. The pivots 10, 11

lie preferably very nearly or entirely in a horizontal plane and preferably at or above the vertical middle of the last, although this exact position depends upon the configuration of the severing line, which may 60 be varied, as will be more apparent later, to some extent without departing from the spirit and scope of my invention. As thus constructed it will be apparent that in the first place the first collapsing or shortening 65 movement of the last must be straight up along the line 4 for a short distance, and in the second place that there is no lengthening whatever of the last as it begins to move away from its position Fig. 1 but it 70 begins to shorten immediately when the heel begins to move. These two points are of practical value in the operation of a last in a shoe factory, and particularly so in a second last or follower.

75 As soon as the heel-part 3 has moved vertically a very short distance it then swings on the pivot 10 as a center and likewise slides, thereby turning slightly also on the pivot 11 until it reaches the position shown 80 in Fig. 2, where it will be seen that the rear end of the oblique cut 6 laps over and rests against the bottom front corner or shoulder of the heel-part. The flat inclined wall, face or secant upper end of the forepart, rests 85 solidly flat against the corresponding broad extended flat area of the wall or secant end 6 of the heel-part. This gives great stability of position when the last is collapsed as shown in Fig. 2. This is the shortened position which it is necessary that the parts should assume when a shoe is to be relasted, i. e., is to be placed again on the last. One of the great practical drawbacks to most lasts is that in relasting, when the last is on 90 a jack with its bottom side up in position for the operator to push the shoe onto the last the forepart will not remain in shortened position but will slide or swing back into lengthened position, under the slight downward pressure which most operators almost invariably use in connection with the forward main shoving pressure exerted on the shoe as it is pushed over the toe of the last toward the heel. My present last overcomes 95 this difficulty however, without requiring any special locks, hinges, or other cumbersome or expensive parts. Because of the slight overhang of the bottom of the forepart on the bottom of the heel-part, and be- 100 105 110

cause of the broad flat abutting surfaces of the forepart and heel-part adjacent the crown, and the direction, location and construction of the single link connecting member, the last invariably remains shortened. By having a single link and having it freely pivoted at its opposite ends so that each last-part can have a slight pivotal movement relatively to the other last-part when not in lengthened position, and by having the upper plane surface from 7 to 8 at an angle to the main inclined or contiguous plane surface 6, the heel-part is permitted to swing under the forepart, when inverted as shown 15 in Fig. 2, and adjust its large plane oblique surface or wall flat against the opposite oblique surface or wall from 7 to 8, and thereby secure a stability of position and firm resistance to the shifting pressure mentioned, 20 when a shoe is being relasted. This stability of position is increased by having provision for a corner or engaging edge at the bottom front end of the heel-part to engage the overhanging sloping or oblique wall 6 near 25 the bottom of the last. Besides this functional advantage, my last is exceedingly strong, as will be evident viewing the large solid blunt-ended shape of the forepart at its severed end and the relatively long and 30 solid adjacent end of the heel-part, neither of which are seriously cut into and have no cuts, formation or applied parts so located or shaped as to tend to give the last a tendency to split lengthwise which construction 35 has proved disastrous to many otherwise excellent constructions. Also by reason of my angular or broken line of cut the forepart of the last is slightly inclosed by the heel-part of the last, so that one part does not tend 40 materially to twist or turn on the other part, and hence, for this reason, a single link is sufficient to join the last even when used as a first last.

One of the main features of my invention 45 resides in providing the forepart with two oblique walls at an angle to each other, and connecting the heel-part by such form of connecting means that it permits the automatic turning or adjustment of the heel-part so as 50 to bring its oblique wall into flat abutting contact against the lower of said two oblique walls of the forepart when the last is in lengthened position and into flat abutting contact against the upper of said two oblique walls of the forepart when the last is in 55 shortened position, said construction effecting said coöperation of the parts in such a manner that the relasting thrusts or pressures are resisted by one face or wall of one 60 last-part bearing flat against the opposite face or wall of the other last-part, and the connecting means is of such a nature and so located that it does not tend to prevent this result, but rather coöperates in aiding it. 65 This feature of my invention is not herein

claimed, but is claimed in my copending application Serial No. 421,521 filed March 16, 1908. I claim herein my specific construction in which the link 12 is employed, having the two pivot pins 10 and 11 snugly fitting the holes or link apertures for pivotal movement only, so that the pins 10 and 11 always remain at invariably the same distance apart, said construction coöperating with the angular line of cut 5, 7, 8 in permitting 70 the peculiar combined swinging and sliding movement already described. Also, while I prefer to stop the inclined wall 6 at the point 5 and thence sever the last-parts along the vertical plane 4, as the simplest means of providing the shoulder or corner of the heel-part, I do not intend to restrict my invention in all cases to this construction as this has the same result, as also the provision of means to prevent lateral 75 shifting and give the parts a tendency to remain in stable lengthened position when the heel-part is swung down as shown in Fig. 1, may be accomplished in various other ways without departing from the spirit and scope 80 of my invention as hereinafter defined in certain of the claims. Accordingly I intend herein to claim the same generically.

Having described my invention, what I claim as new and desire to secure by Letters 95 Patent is,

1. A divided last, having its forepart and heel-part severed by a line of cut and joined by a connecting member, affording a corner having its angular extremity at the front 100 bottom edge of the heel-part, an overhanging inclined wall on the forepart engaged and supported by said angular extremity of said corner when the last is shortened, and flatly abutting oblique secant faces of extensive area at the secant ends of said last-parts adjacent the crown extended forward towards the crown in planes transverse to the general direction of the pressure on the forepart, of a shoe when being shoved rearward on said forepart in being relasted.

2. A divided last, having its parts severed by an angular line of cut extending down from the crown of the last rearwardly in an oblique direction, a single connecting link 115 transversely pivoted at its opposite ends in said respective last-parts approximately midway from the bottom to the top of the last and substantially in a horizontal plane and transverse pivot pins for said connecting link maintained in all positions at the same distance apart, the upper portion of said angular line of cut extending forward in a plane affording flat abutting faces of extensive area transverse to the general direction 120 of the pressure on the forepart, of a shoe when being shoved rearward on said forepart in being relasted, said flatly abutting faces, when in contact with each other, serving to resist said relasting pressure of the 125 130

shoe and aid in preventing the tendency of the last to collapse prematurely and to prevent the tendency of either last-part to turn on its pivot with relation to the other last-part.

3. A divided last, having its forepart provided at its rear end with two transverse secant faces at an angle to each other and both extending obliquely downward toward the heel end of the last, the lower of said two secant faces more nearly approaching the vertical than the upper, and having its heel-part provided with an oblique secant face adapted to coöperate with the lower of said forepart faces when the last is in lengthened position and with the upper of said two forepart faces when the last is in collapsed position, a link apertured at its opposite ends, and transverse pivot pins snugly fitting said apertures for pivotal movement only, said link and pins permanently connecting said forepart and heel-part and permitting the heel-part to adjust its said secant face against the lower forepart face when the last is lengthened and against the upper forepart face when the last is shortened, whereby when the last is in said shortened position

the said two abutting faces tend to aid in maintaining the last in position for receiving a shoe when being relasted.

4. A divided last, having a connecting link pivoted at its opposite ends in the forepart and heel-part respectively approximately half way from the bottom of the last to the top, said forepart being severed from the heel-part by a line of cut extending in a vertical plane upward from the bottom of the last a short distance and thence in a diagonal plane extending upward and forward approximately half the distance to the crown of the last, the upper rear end of the forepart having its secant face in a plane deflected from said point forward at an angle to receive the broad extended face of the heel-part at said oblique plane in flat supporting engagement therewith when the heel-part is swung on said link.

In testimony whereof, I have signed my name to this specification, in the presence of two subscribing witnesses.

EDWIN O. KRENTLER.
